RACING GAME BOARD

John W. Ryan, Bel-Air, and Cecil Frederick Adickes, Jr., Woodland Hills, Calif., assignors to Mattel, Inc., a corporation of California

Filed Jan. 28, 1966, Ser. No. 804

Term of patent 14 years

(Cl. D34—5)

FIG. 1 is a perspective view of a racing game board showing our new design;

FIG. 2 is a top plan view of the design;

FIG. 3 is a side elevational view of the design showing the side opposite to that shown in FIG. 1; and

FIG. 4 is an end elevational view taken from the right as seen in FIG. 2.

We claim:

The ornamental design for a racing game board, as shown.
